UNITED STATES PATENT OFFICE.

GEORGE G. ROSS, OF GREENSBURG, PENNSYLVANIA.

WALL-PAPER TRIMMING, CUTTING, AND PASTING MACHINE.

1,287,757.

Specification of Letters Patent. Patented Dec. 17, 1918.

Application filed September 26, 1917. Serial No. 193,313.

To all whom it may concern:

Be it known that I, GEORGE G. Ross, a citizen of the United States, residing at Greensburg, in the county of Westmoreland 5 and State of Pennsylvania, have invented certain new and useful Improvements in Wall-Paper Trimming, Cutting, and Pasting Machines, of which the following is a specification, reference being had to the accompanying drawings.

This invention comprehends certain new and useful improvements in wall paper trimming, cutting and pasting machines, and the invention has for its primary object a simple, durable and efficient construction of machine of this character, the parts of which may be easily manufactured and readily assembled and not liable to get out of order or require any especial or undue attention in use.

A further object of the invention is a machine of this character which will be light in construction and capable of being easily carried from place to place to the point where it is desired for use, the parts being not only of simple construction, but few in number, and the apparatus being capable of easy actuation by hand.

A still further object of the invention is an improved construction of coating machine of the tank feed, roller and web type, wherein the paste applying rolls are mounted in a tank or paste receptacle which, with the rolls mounted therein, may be easily removed from the machine and readily put back in place after the paste has been received therein, the machine also embodying a paper feeding roller coating with the paste applying rolls to effectively feed the paper over and in contact with the peripheries of said rolls, said feeding roller being mounted within a frame or casing which is detachable from the main framework of the machine, whereby said roller may be easily removed and supported upon arms provided for it, in an inoperative position, while the paper is being first fed to the machine, or while the paste tank or receptacle is being removed, refilled, and replaced.

The invention has for other objects to provide a machine of this character with paper trimming or cutting knives mounted at convenient points, and laterally or otherwise adjustable with guide rolls through which the paper is first fed and with one of which

the knives may coact to trim or cut the paper, with a conveyer of endless apron type arranged in convenient juxtaposition to the other parts of the machine, whereby the coated wall paper will be received directly thereon as it passes away from the paste applying rolls, with measuring devices so that the amount of paper pasted and trimmed may be at all times determined or ascertained, and with a tensioning device for the roll of wall paper that is mounted upon the machine for the pasting operation.

And the invention also aims to generally improve devices of this class so as to render them more useful and commercially desirable.

With these and other objects in view, as will more fully appear as the description proceeds, the invention consists in certain constructions, arrangements and combinations of the parts that I shall hereinafter fully describe and claim.

For a full understanding of the invention reference is to be had to the following description and accompanying drawings, in which—

Figure 1 is a plan view of a machine embodying the principles and improvements of my invention.

Fig. 2 is a longitudinal sectional view thereof, and

Fig. 3 is a side elevation, looking at that side opposite to the one on which the section of Fig. 2 is taken.

Corresponding and like parts are referred to in the following description and accompanying drawings by like reference characters.

Referring to the drawings, the numeral 1 designates the box-like framework of my machine, and upon the sides of said framework and secured to the upper edges thereof are brackets 2 formed with open bearings 3 to support the shaft 4 that carries the roll 5 of wall paper to be pasted, cut and trimmed. Preferably, I provide a tensioning arm 6 which, in the present embodiment of the invention, is pivotally mounted intermediate of its ends, as at 7, upon an upright 8 secured in the framework 1 at one end thereof, a bracket 9 extending out from this end of the framework and carrying a post or rod 10 which is encircled by a helical expansion spring 11, said spring bearing against the rear end of the tension arm 6 whereby

the other and curved end of said arm will bear downwardly with the required tension upon the roll of paper 5.

Secured within this end of the framework 1 is a transversely extending rod 12 which carries any desired number of trimming or cutting knives 13, said knives being of any desired type or design and mounted for lateral adjustment in any desired way. In the 10 present embodiment of the invention, these knives are of the flat blade type, although it is to be understood that the invention is not limited thereto, and they are held at the desired adjustments, laterally considered, by 15 means of set screws 14, as shown.

As the paper is fed from the roll 5 it first passes between upper and lower guide rollers 15 and 16 and if desired the knives 13 may coact with the uppermost guide roller 20 15 for the cutting operation.

The paper, after it passes between the guide rollers 15 and 16 extends over and in contact with two transversely extending paste applying rolls 17 that are mounted 25 within a paste tank or receptacle 18 which is suitably held within a transversely elongated compartment formed in the framework 1 by one end wall 19 thereof and a transversely extending partition 20 spaced 30 therefrom. The tank receptacle 18 has side walls 18^a and end walls 18^b and is provided at one end with a handle 21 whereby it may be easily slipped by lateral movement out from the framework so as to be detached 35 therefrom and receive its supply of paste.

Mounted above and in frictional contact with the peripheries of the paste applying rolls 17 is a feeding roller 22 and the paper is passed between the roller 22 and the paste 40 applying rolls 17 whereby the friction, as the roller 22 is turned, will carry the paper on through the machine while at the same time the rotary movement imparted to the rolls 17 will carry the paste up to the lower 45 or reverse face of the paper and coat the same, the paper, as it passes from the machine, being received upon a conveyer which is preferably of the endless apron type, as indicated at 23, and secured in any desired 50 way in convenient juxtaposition or contiguity to the other elements of the apparatus.

In the preferred embodiment of my invention, the feed roller 22 and the roller 15 55 are mounted in bearings carried by the side walls of a preferably rectangular frame or casing 24 which rests loosely between the inner faces of the sides of the framework 1, the frame or casing 24 being provided with 60 any desired number of handles 26 whereby it may be easily raised and removed from place and supported upon horizontally disposed arms 27 that are secured to the framework 1 as best illustrated in Fig. 2, so that 65 in this inoperative position of said feed

roller, the paper may be easily first fed between the guide rolls 15 and 16 and over the paste applying rolls 17, or the receptacle 18 easily removed to replenish its supply of paste. The forward and rear walls of the 70 frame 24 are designated respectively 24^a and 24^b.

The shaft of the feed roller 22 is extended at one end, as indicated at 28, so as to extend through a slot in the frame 1 and has there 75 secured to it a crank handle 29 whereby it may be easily turned, and by frictionally engaging the paste applying rolls 17 with the paper interposed between, effect the rotation of said paste applying rolls and the operation of coating the reverse side of the 80 wall paper.

In the present embodiment of the invention the shaft 28 also carries a spur gear 30 which meshes with an idler 31 mounted on 85 the adjacent side of the framework 1, said idler being mounted on the same shaft with the spur pinion 32 and the latter meshing with a spur gear 33. This last named gear has any desired units or figures displayed 90 thereon, these figures designating the length of paper unwound from the roll 5 and pasted, the figures being seen through an opening 34 which is formed in a plate 35 secured to the framework, as best illustrated 95 in Fig. 3.

The spur gear 30 also meshes with an idler gear 36, and this in turn meshes with a gear 37 secured to the shaft 38 by one of the rollers 39 of the endless or apron 100 conveyer 23 whereby the latter is actuated.

The rollers 17 are preferably detachably mounted within the tank or receptacle 18 and to this end the tank 18 is provided with laterally disposed supporting members 40 105 having bearings for the rollers 17, these members 40 being adapted to be removed from the tank 18 to permit the tank to be thoroughly cleaned. Disposed at the forward end of the tank 18 and extending transversely thereacross is a loose bar 41, the edge of which is upwardly and rearwardly beveled to conform fairly closely to the forward roller 17, this bar resting in recesses in the end walls of the tank and being removable to permit removal of the members 40. This loose bar prevents the paper from 110 following the forwardmost roller 17 down into the paste and guides the paper on over to the endless carrier 23.

From the foregoing description, in connection with the accompanying drawings, the operation of my improved wall paper machine will be apparent. In the practical use of this device the tank or receptacle 18 is provided with paste, then the rod 4 is removed from the bearings in the brackets 2 and a roll of wall paper is placed upon this rod. The knives 13 are then longitudinally adjusted upon the rod 12 so as to trim 125

the paper properly or cut it into strips and the paper is drawn out so as to extend beyond the foremost roller 17. The frame 24 is then disposed in place with its shaft 28 5 extending through the slot in the side of the outer frame and the weight of this frame 24 and the rollers 22 and 15 forces the paper down into contact with the rollers 16 and 17, the gear 30 meshing with the 10 gears 36 and 31.

Now upon a rotation of the crank 29 it will be obvious that the paper will be fed between the guide rolls 15 and 16 and between the feed roller 22 and the roller 17, 15 the paper will be cut and paste will be applied thereto. The paper in its pasted condition will be received upon a conveyer 23 whence it can be removed as required. When it is desired to clean the paste tank 20 18, the operator may withdraw the paste tank from the main frame and turn the paste tank upside down and then lift the paste tank up permitting the two rollers 17 and their bearing members 40 to drop 25 out. After cleaning the rollers and bearings, the operator can drop the bearings and rollers in place again and the device is ready to be returned to its position in the main frame. It will thus be seen that I 30 have provided a very simple, durable and efficient construction of machine of this character which will be light and strong in its construction and capable of being easily carried from place to place as its services 35 are required.

While the accompanying drawings illustrate what I believe to be the preferred embodiment of my invention, it is to be understood that the invention is not limited there- 40 to but that various changes may be made in the construction, arrangements and proportions of the parts without departing from the scope of the invention as defined in the appended claims.

45 What is claimed, is:

1. A paste applying machine including a main frame, a paste receptacle mounted therein and removable laterally therefrom, paste applying rolls mounted in and carried 50 by said receptacle, an auxiliary frame removably mounted in the main frame above said receptacle, and a web feeding roller mounted in and carried by said auxiliary frame and disposed in a vertical plane be- 55 tween the paste applying rolls so as to hold a web thereto and extending downward be- tween the paste applying rolls and bearing downward on the web of paper by gravity.

2. In a machine of the character de- 60 scribed, a main frame provided with a laterally opening compartment, a paste recep- tacle receivable in and removable from said compartment by a sidewise movement, paste applying means mounted in and carried by 65 said receptacle, a removable auxiliary frame

mounted in the main frame above said compartment, a web feeding device mounted in and carried by said auxiliary frame and adapted to coact with said paste applying devices for applying paste to the web passed 70 therebetween and said feeding device, and horizontally disposed arms secured to said main frame and upon which said auxiliary frame is adapted to rest when removed from its operative position above said compart- 75 ment.

3. In a machine of the character de- 80 scribed, a main frame provided intermediate of its ends with a transverse partition forming with one end wall of the main frame, a transversely elongated compartment, a paste receptacle removably mounted in said compartment, a paste applying roll mounted in said receptacle, an auxiliary frame removably mounted in the main frame above 85 said compartment, a feeding roller journaled in said auxiliary frame, guiding rolls journaled in advance of said compartment and the paste receptacle and said auxiliary frame, supporting means for a roll of paper 90 carried by said main frame above said guide rolls, and trimming means mounted in the main frame between said supporting means and said guide rolls.

4. A machine of the character described 95 comprising a main frame, paper supporting means carried thereby near one end of the same, tensioning means for a roll of paper carried by the paper supporting means, the main frame being provided with a trans- 100 versely extending partition spaced from one end thereof and forming a laterally elongated compartment, guide rolls operatively mounted in said main frame between said partition and the other end of the frame- 105 work, paper cutting devices mounted be- 110 tween said guide rolls and the last named end of the main frame, a paste receptacle removably mounted within said compart- 115 ment, a paste applying roll mounted in and carried by said receptacle, an auxiliary frame removably mounted in the main frame above said receptacle, a paper feeding roller mounted in and carried by said auxiliary frame and adapted to coact with the 120 paste applying roll, and arms secured to and extending rearwardly from the main frame at opposite sides of the latter and upon which said auxiliary frame is adapted to be supported in its inoperative position.

5. A paste applying device comprising a main frame, a guide roller journaled therein, a paste tank disposed in advance of the guide roller, paste applying rolls mounted in the paste tank, and an auxiliary frame 125 operatively supported in the main frame above the paste tank, a guide roller journaled in the auxiliary frame and coacting with the first guide roller, and a feed roller journaled in the auxiliary frame and dis- 130

posed in a plane between the paste applying rollers and resting thereagainst, and means for rotating the feed roller.

6. A paste applying device including a main frame, a paste tank, paste applying rollers disposed within the paste tank, oppositely disposed supporting members loosely mounted within the paste tank and supporting said paste applying rollers, a feed roller operatively supported on the main frame and normally urged toward said paste applying rollers to force a web against these rollers.

7. A paste applying device comprising a main frame having an opening in one side at the forward end of the frame, a guide roller journaled in the main frame, a paper roll supporting rod journaled on the main frame above the guide roller, a paste tank disposed in the main frame and removable through said opening, paste applying rollers mounted in the tank, a removable auxiliary frame mounted in the main frame, and a guide roller mounted in the auxiliary frame and coacting with the first named roller, and feed rollers mounted in said auxiliary frame and coacting with the paste applying rollers.

8. In a device for applying paste to webs, a main frame, a paper roll supporting shaft mounted thereon, guide rollers operatively supported in the frame below said shaft and coacting with each other, paste applying de-

vices disposed in advance of the guide rollers, a transverse rod disposed rearward of the guide rollers, cutter supporting arms mounted on said rod for rotative adjustment therearound and longitudinal adjustment therealong, and cutting blades carried on and rigid with said members.

9. A paste applying device comprising a main frame, bearings mounted upon the frame and extending upward thereabove, a paper roll supporting shaft detachably mounted in the bearings, a laterally removable paste tank mounted in the forward end of the frame, a guide roller mounted in the frame rearward of the paste tank, a pair of paste applying rollers mounted in the tank, an auxiliary frame removably disposed within the main frame, a guide roller journaled therein and removable therewith and coacting with the first named guide roller, a feed roller journaled therein and coacting with the paste applying rollers, means for rotating the feed roller carried by said auxiliary frame, and means mounted on the main frame engaging the roll of paper on the shaft and resisting rotation of said roller to feed the paper.

In testimony whereof I hereunto affix my signature in the presence of two witnesses.

GEORGE G. ROSS.
